(57) CLAIM

The ornamental design for a vaping apparatus with a removable adapter as shown and described.

DESCRIPTION

FIG. 1 is a top, front, and right side perspective view of a vaping apparatus with a removable adapter according to the novel design.

FIG. 2 is a bottom, rear, and right side perspective view of the vaping apparatus with a removable adapter depicted in FIG. 1.

FIG. 3 is a front view of the vaping apparatus with a removable adapter depicted in FIG. 1.

FIG. 4 is a rear view of the vaping apparatus with a removable adapter depicted in FIG. 1.

FIG. 5 is a right side view of the vaping apparatus with a removable adapter depicted in FIG. 1.

FIG. 6 is a left side view of the vaping apparatus with a removable adapter depicted in FIG. 1.

FIG. 7 is a top view of the vaping apparatus with a removable adapter depicted in FIG. 1; and,

FIG. 8 is a bottom view of the vaping apparatus with a removable adapter depicted in FIG. 1.

The broken lines included in the drawings depict elements of the vaping apparatus with a removable adapter that are not part of the claimed design.

1 Claim, 8 Drawing Sheets
